TOY HOUSE BOAT

Victor G. Reiling, Jr., East Aurora, N.Y., assignor to
The Quaker Oats Company, Chicago, Ill.

Filed Dec. 6, 1972, Ser. No. 312,591

Term of patent 14 years

Int. Cl. D21—01
U.S. Cl. D34—15 JJ

FIG. 1

FIG. 2

FIG. 3

FIG. 4

FIG. 5

FIG. 1 is a front perspective view of a toy house boat showing my new design;

FIG. 2 is a side elevational view thereof as viewed from the opposite side of FIG. 1;

FIG. 3 is a bottom plan view thereof;

FIG. 4 is a front elevational view thereof; and
FIG. 5 is a rear elevational view thereof.

I claim:

The ornamental design for a toy house boat, substantially as shown.
